* cited by examiner

Primary Examiner — Sandra L Morris(74) *Attorney, Agent, or Firm* — AEON Law, PLLC;
Adam L. K. Philipp; Martin Spencer Garthwaite(57) **CLAIM**

The ornamental design for an infant sleeping aid, as shown and described.

DESCRIPTION

FIG. 1 is a front elevation view of an infant sleeping aid;

FIG. 2 is a rear elevation view thereof;

FIG. 3 is a left side elevation view thereof;

FIG. 4 is a right side elevation view thereof;

FIG. 5 is a bottom plan view thereof;

FIG. 6 is a top plan view thereof; and,

FIG. 7 is a front perspective view thereof.

The broken lines of FIGS. 1-7 illustrate portions of the infant sleeping aid, or illustrate environmental matter, that form no part of the claimed design.
